UNITED STATES PATENT OFFICE.

GEORGE S. DARLING, OF CHICAGO, ILLINOIS, ASSIGNOR TO THE WILSON SEWING MACHINE COMPANY, OF SAME PLACE.

DESIGN FOR SEWING-MACHINE STANDS.

Specification forming part of Design No. **11,195**, dated May 13, 1879; application filed January 15, 1879.
[Term of patent 14 years.]

To all whom it may concern:

Be it known that I, GEORGE S. DARLING, of Chicago, in the county of Cook and State of Illinois, have invented a new Design for Sewing-Machine Stands; and I do hereby declare that the following is a full, clear, and exact description of the same.

My invention relates to a novel design for the legs of a sewing-machine stand; and it consists in the peculiar conformation of the bars thereof, forming the letters W and M, united by the letters "S. Co.," as a monogram, as hereinafter fully described.

Referring to the drawings, I make the W form the upper part of the frame, as at B, the M, I make to form the lower part of the frame, as at A, and the "S. Co.," I arrange as a monogram in the middle, joining the lower points of the W and the upper points of the M, as shown. Now, inasmuch as a W is the same as an inverted M having its outer lines spread apart, it will be seen that these letters, when arranged as described, produce a perfectly symmetrical leg of artistic and significant shape.

For greater strength, the tops of the limbs of the W and the bottom of the limbs of the M are connected by curved bars C and D.

I do not claim, broadly, a design composed of the letters "W. S. M. Co.," but

What I claim is—

1. A design for a sewing-machine leg, composed of an arrangement of bars formed at the upper part into a W, and formed at the lower part into an M, to give symmetrical ends, and the two parts joined in the middle by the letters "S. Co.," as a monogram, as shown and described.

2. A design for a sewing-machine leg, composed of a W at the upper part, having its upper ends connected by a curved bar, C, an M at the lower part, having its lower ends connected by a curved bar, D, and the two parts joined by the letters "S. Co.," as a monogram, in the middle, substantially as shown and described.

GEO. S. DARLING.
